UNITED STATES PATENT OFFICE.

CHARLES MCKEEVER, OF JERSEY CITY, NEW JERSEY.

BOTTLE-STOPPER.

1,131,400.

Specification of Letters Patent.

Patented Mar. 9, 1915.

Application filed February 27, 1914. Serial No. 821,363.

To all whom it may concern:

Be it known that I, CHARLES MCKEEVER, a citizen of the United States, residing at Jersey City, in the county of Hudson and 5 State of New Jersey, have invented an Improvement in Bottle-Stoppers, of which the following is a specification.

My present invention relates to a bottle stopper, and particularly to that class of 10 bottle stoppers in which a valve is employed to close the outlet or discharge port of the stopper when the bottle is in pre-determined positions, in order to prevent the flow of a liquid into the bottle.

15 In carrying out my present invention, I simplify the construction by eliminating the weight of ball member ordinarily employed for returning and maintaining the shut-off valve against its seat when the bottle is being returned to its upright position, and to 20 accomplish this object, I prefer to employ a conical valve and a guide upon which the same slides so as to return to its seated position at or just prior to such a time as the 25 bottle, in being returned to its upright position, reaches a position in which the body of the bottle is horizontal, as will be herein-after more particularly described.

In the drawing, Figure 1 is a central longitudinal cross section illustrating my present invention. Fig. 2 is a similar view showing the parts in position, which is assumed when the contents of the bottle are being poured therefrom. Fig. 3 is also a 35 similar view showing a modified form of the invention, and Fig. 4 is a perspective view of the member employed to co-act with the valve.

Referring to the drawing, and particularly 40 to Figs. 1 and 2, 10 indicates the upper portion of the body of a bottle having a neck 11 adapted to be fitted with the stopper 12, in which there is a central port or aperture 13. The mouth of the bottle may be fitted 45 with a cap 14 of the Crown Seal type, or otherwise. Interiorly, the neck of the bottle is provided with a flange 15, the upper surface of which comprises or provides for the valve seat 16, which rests against the upper 50 or outer surface of the flange 15, suitably secured in position and centrally provided with a discharge port 22. Between the valve seat and the inner end of the stopper, I prefer to employ an annular plate 17 provided 55 in spaced positions with arms 18, adapted to be forced into or otherwise con-

nected to the stopper, in order to support the annular plate 17 and parts associated therewith in position. Associated with the annular plate 17 is a ring 19. This may be 60 connected to the annular plate by arms 20, or otherwise. Within the chamber provided between the inner end of the stopper and the upper ends of the valve seat in the neck of the bottle, I employ a conical valve 65 21. The base of the conical valve is of sufficient area or extent to completely cover the port 22 in the valve seat member 16, in any position in the chamber in the neck of the bottle which the said valve may assume 70 when the bottle is in an upright position or any position between the same and a horizontal position. In pouring the contents from the bottle, the conical valve, as will be readily understood, falls from its seated position and a greater portion of the same lies 75 within the ring 19 and bears against the sides of the same. One of the positions which this valve may assume in the emptying of the bottle is illustrated in Fig. 2. In 80 returning the bottle to its upright position, as will be apparent, when the same reaches the horizontal position the surface of the conical valve will slide against the edge of the ring, and, due to its own weight, or by 85 the action of gravity, the valve will return to its seated position by or before the time the bottle reaches a horizontal position.

Referring to Fig. 3, it will be seen that in carrying out my invention, I may employ a 90 pair of stoppers 27 and 28, to the inner side of each of which tubes 29 and 32 are suitably connected. As illustrated, the tube 29 is provided with a flange 30, bearing against the under surface of the stopper 27, and also 95 with suitable discharge ports 31, while similarly the tube 32 is provided with a flange 33 bearing against the under surface of the stopper 28 and is also provided with suitable ports 34. The conical valve 35 is employed in the chamber between the stoppers 27 and 28, and co-acts with the tube 29 to 100 close the port in the stopper 28, while the valve 36 co-operates with the tube 32 to close the discharge port in the valve seat member 16. In this construction, as will be observed, 105 it will be unnecessary to employ the annular plate member 17, or its equivalent, inasmuch as the valve 35 will prevent tampering with the inner valve 36.

As will be seen by reference to the drawing, I prefer to employ a cork or other stop-

per, indicated at 37, in the opening or port in the annular plate 17, so that in the event of attempts being made to hold the conical valve away from its port, in re-filling the bottle, or otherwise tampering with the stopper, this cork 37 will be forced inwardly against the upper or outer end of the conical valve, forcing it against its seat and thus forcing the parts of the stopper to that position in which the bottle would neither be emptied or re-filled. For a like purpose, I may also employ a cork 38 within the tube 29, as is shown in Fig. 3.

I claim as my invention:

- 15 1. In a non-refillable bottle, a stopper comprising a conical valve, a valve seat for the same, in which there is a discharge port, a ring co-acting with the inclined surface of the valve for returning the same to its seated position in righting the bottle, and a movable member normally seated adjacent the said ring and movable into the same to force and permanently maintain the said valve against its seat in attempts to tamper with the stopper.
- 20 2. In a non-refillable bottle, a stopper comprising a conical valve, a valve seat for the

same provided with a discharge port, a ring co-acting with the inclined surface of the valve for returning the same to its seated position in righting the bottle, an annular plate, means for securing the said ring and annular plate together and in position in the stopper, and a movable member normally lying within the opening in the said annular plate and movable to a position within the said ring to force and maintain the said valve against its seat.

3. In a non-refillable bottle, a conical valve, a valve seat for the same, having a discharge port therein, a stopper, a ring co-acting with the said conical valve and upon which the same slides upon returning to its seated position, an annular plate to which the said ring is connected, a device for normally closing and opening the said annular plate, and means for connecting the said annular plate and ring to the said stopper.

Signed by me this 23d day of February, 1914.

CHARLES McKEEVER.
